ATTORNEY

UNITED STATES PATENT OFFICE.

STANLEY SEPTIMUS BOOTY, OF LONDON, ENGLAND.

BOX AND THE LIKE.

1,424,071.

Specification of Letters Patent. Patented July 25, 1922.

Application filed July 7, 1920. Serial No. 394,452.

To all whom it may concern:

Be it known that I, STANLEY SEPTIMUS Booty, a subject of the King of Great Britain and Ireland, and residing at 51 Lexham 5 Gardens, Earls Court, London, W., England, have invented certain new and useful Improvements in and Relating to Boxes and the like, of which the following is a specification.

10 This invention relates to boxes and the like of the kind in which the lid has a downwardly projecting curved collar, adapted to be engaged about the side walls of the box or an upwardly projecting rim or collar attached to or forming part of or constituting said side-walls.

15 In forming such boxes of certain materials as for instance cardboard, it is found that it is difficult to ensure that the lid fits tightly on the body of the box as atmospheric conditions cause expansion or contraction of the material employed in the construction thereof, with the result that a lid which may be a good fit in some circumstances will be too tight or too loose in others.

20 The object of the present invention is to provide means whereby a satisfactory frictional engagement of the lid and the body of the box may be ensured.

25 According to the invention, the downwardly projecting collar of the lid or the upwardly projecting rim or collar attached to or forming part of or constituting the side-walls of the box is provided with a plurality of holes, spaced apart circumferentially on the collar and a ribbon, cord or the like is threaded through these holes.

30 Ordinarily, these holes are provided at suitable intervals round the said collar, and the ribbon, cord or the like is passed through successive holes in an inward and outward direction alternately, the ends of the ribbon being secured together, optionally in such manner that the tension on the portion of the ribbon, cord or the like threaded through the holes may be varied in order to secure a tighter or looser fit of the lid.

35 When necessary or desirable a washer of resilient or flexible material may be arranged in the lid or on the upper edge of the side-walls of the box so as to secure a dust-tight closure, or other means adapted to effect this result may be provided.

40 The invention is of utility in connection

with receptacles for powder as claimed in the specifications of my prior applications for British Letters Patent Nos. 18690, 20430 and 20431 of A. D. 1918 and 3034 of A. D. 1919, as well as for other receptacles for powder of the kind in which a foraminous surface is arranged above the powder contained in a box of the kind first above referred to, and such receptacles, provided with the means whereby a satisfactory engagement of the lid and body of the box may be ensured, specified above, fall within the scope of the present invention.

45 Certain constructions in accordance with the invention are illustrated, by way of example, in the accompanying drawings, in which:—

50 Figures 1 and 2 are views of one construction;

55 Figures 3 and 4 are views of a second construction; and

60 Figures 5 and 6 are views of a third construction.

65 In the drawings 1 is the downwardly projecting collar of the lid, 2 the upwardly projecting rim or collar forming the side-walls of the box. 3 are holes provided in the collar, 4 is the ribbon threaded through said holes and tied in a bow 5. As will be seen the construction illustrated in Figures 70 3 and 4 is differentiated from the construction illustrated in Figures 1 and 2 by the positioning of the holes.

75 The construction illustrated in Figures 5 and 6 has two pairs of holes with a piece 90 of ribbon threaded through each pair, the ends of each piece of ribbon being tied in a bow on the outside of the lid. In these last mentioned figures the present invention is illustrated as applied to the construction of 95 a receptacle for powder as claimed in the specifications of British Letters Patent Nos. 18690, 20430 of A. D. 1918 and 3034 of A. D. 1919, 6 indicating the puff device, 7 the foraminous surface and 8 the spring supporting the latter.

80 It is to be observed that the employment of a ribbon, cord or the like in the manner indicated, does not effect the desired results in consequence of the contraction of the 105 downwardly projecting collar under the tension put upon the ribbon, cord or the like, but as the result of the ribbon, for instance, within the collar extending between the holes in a more or less taut manner grip- 110

ping more or less tightly about the walls of box or the collar forming part of the same.

In the appended claim the expression 5 "ribbon" is to be construed as including cord or equivalents.

Further it is to be understood that providing the side walls of the body portion of the box with holes and threading a ribbon 10 through such holes in order to ensure a satisfactory frictional connection between the lid and body portions is an obvious alternative to arranging a ribbon or the like in holes in the lid and as such is included within 15 the scope of the patent claim.

Having now described my invention what I claim as new and desire to secure by Letters Patent is:—

A box comprising lid and body portions adapted to be telescopically engaged one 20 with the other and having curved walls, holes spaced apart circumferentially in the wall of the lid portion, a band threaded through the holes and stretched sufficiently taut between them to secure a firm frictional 25 connection between the lid and body portions.

In testimony whereof I have signed my name to this specification.

STANLEY SEPTIMUS BOOTY.
